WASH BASIN, TOILET BOWL, AND BIDET COMBINATION

Ernest Amery, New York, N.Y.

Application August 29, 1958, Serial No. 52,439

Term of patent 14 years

(Cl. D4—4)

FIG. 1

FIG. 3

Fig. 1 is a top plan view of a wash basin, toilet bowl and bidet combination, showing my new design.

Fig. 2 is a front elevation thereof.

Fig. 3 is a perspective view thereof.

I claim:

The ornamental design for a wash basin, toilet bowl and bidet combination, substantially as shown.
